(57) **CLAIM**

The ornamental design for an applique for motor vehicle, as shown and described.

DESCRIPTION

FIG. 1 is a perspective view showing an applique for motor vehicle assembled to a representative vehicle.

FIG. 2 is a front top perspective view of the applique for motor vehicle shown in FIG. 1;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a rear view thereof.

Where utilized, the dash-dot chain broken lines represent the bounds of the claimed design while the dashed broken lines show portions of the representative vehicle and portions of the applique for motor vehicle that form no part of the claimed design.
